UNITED STATES PATENT OFFICE

ISAAC L. STEPHENSON, OF DARROUZETT, TEXAS

MEANS FOR TIGHTENING THE PLATFORM CANVAS OF COMBINED HARVESTER THRASHERS

Application filed May 29, 1930. Serial No. 457,285.

The invention relates to means for tightening the platform canvas of combined harvester-thrashers.

The object of the present invention is to provide simple, practical and efficient means of strong, durable and comparatively inexpensive construction for tightening the platform canvas of combined harvester-thrashers and to provide a tightening means of this character adapted to enable the platform belt to be loosened at the end of a day's work to prevent absorption of moisture by the platform canvas during the night from bursting, weakening or otherwise injuring the platform canvas and capable of enabling the platform canvas to be readily tightened by the operator as required during operations without leaving his position on a combined harvester-thrasher.

20 A further object of the invention is to provide tightening means for a platform canvas adapted to enable the platform canvas of a combined harvester-thrasher to be conveniently tightened and loosened independent of the machine's operation.

With these and other objects in view, the invention consists in the construction and novel combination and arrangement of parts hereinafter described, illustrated in the accompanying drawings and set forth in the claims hereto appended, it being understood that various changes in the form, size, and minor details of construction, within the scope of the claims, may be resorted to without departing from the spirit of the invention or sacrificing any of the advantages thereof.

In the drawings:

Figure 1 is a side elevation of a portion 40 of a platform provided with a canvas tightening means constructed in accordance with this invention.

Fig. 2 is a plan view of the same partly in section.

45 Fig. 3 is an end elevation of the platform and canvas tightening means.

In the accompanying drawings in which is illustrated the preferred embodiment of the invention, 1 designates the main frame of a 50 platform provided at its opposite sides at

one end with transversely aligned longitudinal slots 2 open at their outer ends and forming guides for a horizontal shaft 3 upon which is loosely mounted a roller 4 which receives the platform canvas 5 at one end of the platform and which may be constructed of wood, steel or any other suitable material. The roller 4 which turns freely on the shaft 3 does not constitute a drive for the platform canvas and the shaft 3 upon which the roller is mounted has keyed or otherwise fixed to it cog wheels 6 which mesh with rack bars 7 located above and arranged in parallelism with the guide slots 2.

The rack bars 7 which are locked at opposite sides of the platform frame are preferably in the form of brackets and are provided at their ends with inner and outer attaching arms 8 and 9 as clearly illustrated in Fig. 1 of the drawing. The shaft is adapted to be moved longitudinally of the guide slots 2 and when moved inwardly or outwardly by the means hereinafter described, the gears 6 which mesh with the rack bars are caused to rotate so that both ends of the shaft are moved simultaneously and uniformly inwardly or outwardly along the guide slots to tighten or loosen the platform canvas. Instead of providing the slots shown in the drawing any other suitable guiding means for the shaft 3 may, of course, be employed and the said shaft rotates only when it is moved inwardly and outwardly for tightening or loosening the platform canvas.

The operating mechanism for moving the shaft inwardly and outwardly to tighten or loosen the platform belt comprises an operating lever 10 and a connecting rod 11 which is provided at its outer end with a ring 12 forming a central circular opening to receive the shaft and permitting the latter to rotate in it. The ring 12 is retained on the shaft by a cotter pin 13, but any other suitable means may, of course, be employed for securing the bearing end of the connecting rod 11 to the shaft and the bearing end may be of any other desired formation to provide a bearing opening for the shaft. Also a washer 14 may be interposed between the cotter pin and the

bearing end of the connecting rod 11, as illustrated in Fig. 3 of the drawing.

The operating lever 10 is fulcrumed intermediate of its ends at 15 on a bracket 16 to provide a relatively short lower arm and a 5 relatively long upper arm. The lower arm is connected by a suitable pivot 17 with the inner end of the connecting rod 11 and the upper end of the long arm is designed to be equipped with a rope 18 or other suitable flexible connection adapted to enable the lever to be manipulated by the operator from his seat on a combined harvester-thresher without leaving his position or relinquishing his control of the machine.

15 The bearing or supporting bracket 16 is provided with a substantially semi-circular top portion having ratchet teeth 19 and forming a segmental ratchet member which is engaged by a spring actuated pawl 20 pivotally mounted on the upper arm of the lever at 21 and controlled by a latch lever 22. The latch lever 22 is connected by a rod 23 or other suitable means with the pawl 20 and it 25 passes through a guide 24 mounted on the upper arm of the lever and forming an abutment for the upper end of the coiled spring 25 which is interposed between the guide 24 and the pawl 20 for urging the latter downwardly to maintain the same in engagement with the segmental ratchet member. It will 30 be clear that a pull on the rope will move the shaft outwardly to stretch the platform canvas and that as the canvas slacks during the 35 operation of the machine it may be tightened and maintained taut without the operator leaving his seat on the machine and without interfering with or stopping the operation of the machine.

40 What is claimed is:—

1. In a tightener of the class described, the combination of a platform frame provided with longitudinal guides open at their outer ends, a shaft extending across the platform frame from one side to the other movable along the guides and having a canvas receiving roller loosely mounted on it, gears fixed to the shaft, fixed rack bars mounted upon the platform frame and located above the 45 gears and meshing with the same for causing uniform movement of the shaft along the said guides when pressure is applied to either end of the shaft to move the latter, and means connected only with one end of the shaft for moving the shaft inwardly and outwardly and for holding the shaft in its adjustment without stopping a machine.

2. In a tightener of the class described, the combination of a platform frame provided with longitudinal guides open at their outer ends, a shaft extending across the platform frame from one side to the other movable along the guides and having a canvas receiving roller loosely mounted on it, gears fixed to the shaft, fixed rack bars mounted upon the

platform frame and located above the gears and meshing with the same for causing uniform movement of the shaft along the said guides when pressure is applied to either end of the shaft to move the latter, a connecting rod having a bearing portion arranged on the shaft at one end thereof, an operating lever connected with the other end of the said rod for moving the shaft inwardly and outwardly without stopping a machine, and means for securing the lever in its adjustment.

3. In a tightener of the class described, the combination of a platform frame provided with longitudinal guides open at their outer ends, a shaft extending across the platform frame from one side to the other movable along the guides and having a canvas receiving roller loosely mounted on it, gears fixed to the shaft, fixed rack bars mounted upon the platform frame and located above the 80 gears and meshing with the same for causing uniform movement of the shaft along the said guides when pressure is applied to either end of the shaft to move the latter, a connecting rod having a bearing portion arranged on the shaft at one end thereof, an operating lever connected with the other end of the said rod for moving the shaft inwardly and outwardly without stopping a machine, a bracket supporting the lever and provided with a segmental ratchet member, a pawl carried by the lever and engaging the ratchet for locking the lever against movement in one direction, and means connected with the lever for moving the same in the opposite direction, said pawl and ratchet member being arranged to permit the canvas to be progressively tightened by the means for operating the lever.

105 In testimony whereof I have hereunto set my hand.

ISAAC L. STEPHENSON.
